(57) CLAIM

We claim the ornamental design for a cover for instrument panel of a car, as shown and described.

DESCRIPTION

FIG. 1 is a front perspective view of a cover for instrument panel of a car showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a cross-sectional view taken through line 8-8 of FIG. 6.

The broken lines in the figures show portions of the cover for instrument panel of a car which form no part of the claimed design.
